FOOTBALL KICKING TEE

Joseph M. Ponder, 6593 Evelyn Drive,
Middletown, Ohio 45042

Filed Aug. 31, 1972, Ser. No. 285,498

Term of patent 14 years

Int. Cl. D21—02

U.S. Cl. D34—5 GT

Fig. 1

Fig. 2

Fig. 3

Fig. 4

Fig. 5

Fig. 6

FIG. 1 is a perspective view of a football kicking tee;

FIG. 2 is a top plan view thereof;

FIG. 3 is a bottom plan view thereof;

FIG. 4 is a side elevational view thereof;

FIG. 5 is a front elevational view thereof; and

FIG. 6 is a rear elevational view thereof.

The side opposite to that shown in FIG. 4 is a mirror image thereof.

I claim:

The ornamental design for a football kicking tee, as shown and described.
